(57) **CLAIM**

(22) Filed: **Jul. 9, 2003**

The ornamental design for a reel seat for fishing rod, as shown and described.

(30) **Foreign Application Priority Data**

Jan. 10, 2003 (JP) 2003-000485

DESCRIPTION

(51) LOC (7) Cl. **22-05**

FIG. 1 is a perspective view of the top, front and left end of a reel seat for fishing rod showing my new design; FIG. 2 is a perspective view of the bottom, rear and right end view thereof;

(52) U.S. Cl. **D22/142**

FIG. 3 is a front elevational view thereof;

(58) Field of Search D22/142, 137-140;

FIG. 4 is a rear elevational view thereof;

43/20, 22, 18.1, 23

FIG. 5 is a top plan view thereof;

FIG. 6 is a bottom plan view thereof;

FIG. 7 is a left end elevational view thereof;

FIG. 8 is a right end elevational view thereof;

FIG. 9 is a sectional view taken on line 9—9 in FIG. 3; and,

FIG. 10 is a sectional view taken on line 10—10 in FIG. 7.

The broken line showing of environment in the drawings is for illustrative purposes only and forms no part of the claimed design.
